UNITED STATES PATENT OFFICE.

ALF LANDGREN AND MAX B. EWERS, OF HIGHLAND PARK, MICHIGAN.

IGNITION-LOCK FOR MOTOR-VEHICLES.

1,325,521.

Specification of Letters Patent. Patented Dec. 23, 1919.

Application filed January 17, 1918. Serial No. 212,199.

To all whom it may concern:

Be it known that we, ALF LANDGREN and MAX B. EWERS, citizens of the United States, residing at Highland Park, in the 5 county of Wayne and State of Michigan, have invented a new and useful Ignition-Lock for Motor-Vehicles, of which the following is a specification.

This invention relates to ignition locks 10 for motor vehicle engines, and it is the object of the invention to make provision against the unauthorized use of a motor vehicle by associating with the spark-plugs of the engine a means for short-circuiting 15 the same when the engine is idle to prevent the effective closing of the ignition circuit, said means being actuatable from the dash of the vehicle through key-controlled mechanism which is so housed and incased as to 20 effectively prevent tampering therewith.

In attaining this object the invention contemplates associating with the spark plugs a rock-shaft, carrying a plurality of contact arms engageable with the respective 25 plugs in one position of said shaft, which is housed together with the plugs in a casing comprising a lower portion permanently secured to the cylinder heads of the engine, and an upper portion removable only by 30 manipulation of key-controlled mechanism, which may, if desired, be the same mechanism whereby the rock-shaft is actuatable.

This object is attained by the construction hereinafter described and illustrated in 35 the accompanying drawings, wherein,

Figure 1 is a view showing in side elevation the upper portion of the cylinders of a motor vehicle engine having associated therewith a preferred embodiment of the 40 present invention, the removable portion or cover of the casing being omitted.

Fig. 2 is a plan view of the same showing in section the housing for the key-controlled mechanism.

Fig. 3 is a longitudinal vertical section, the casing being shown complete, and the section being taken on line 3—3 of Fig. 2.

Fig. 4 is a cross-section through the casing on dotted line 4—4 of Fig. 3 and indicating by dotted lines an actuated position of the locking mechanism.

Fig. 5 is a similar view in cross section on dotted line 5—5 of Fig. 3.

In these views, the reference character 1 55 designates the engine cylinders of a motor vehicle, and 2 the spark-plugs of said cyl-

inders. 3 is a cable formed by a plurality of conductors 4 which are individually led to the several spark-plugs. As a provision for simultaneously short-circuiting said 60 plugs, a rock-shaft 5, grounded to the cylinders, is mounted adjacent the plugs and a plurality of contact arms 6 are so positioned upon said rock-shaft that a slight rotation of the latter will bring them to bear respectively upon the plugs. The rock-shaft is adapted to be actuated through a key-controlled mechanism, 7 being a key insertible in a lock 8 to turn a barrel 9 from which barrel an arm 10 projects for engagement with 70 an arm 11 upon the rear end of the rock-shaft. When the lock barrel is turned in one direction, the arm 10, acting upon the arm 11, rotates the rock-shaft in a direction such as to raise the contact-arms 6 from the 75 spark-plugs, and upon turning of the lock barrel in the other direction, the arms 6 are lowered so that they may engage the spark plugs owing to the action of a coiled spring 12 upon the rock-shaft. Since tampering 80 with the mechanism just described must be prevented, there is provided a casing for said mechanism which forms also a mounting therefor. The lower portion of this casing is permanently attached to the cylinders 85 and comprises a bottom 13, orificed at 14 to fit over the spark-plugs, and double side walls 15 maintained in a fixed spaced relation by blocks 16. A housing 17 for the actuating mechanism is also included in the 90 fixed portion of said casing, said housing being located preferably in an opening 18 in the dash 19 so that the lock 8 which is mounted in the rear wall of said housing may be readily accessible from the driver's 95 seat of the motor vehicle. At one end the rock-shaft 5 is journaled in the front wall of the housing 17, and a bracket 20 forms a bearing for the other end of said rock-shaft, said bracket being mounted upon an upright 100 plate 21 at the front of the casing. The upper portion of the casing is detachable and comprises a top 22, sides 23 and an end wall 24, the lower edges of the side walls being insertible between the double side walls 15 105 and being each formed with a plurality of bayonet tongues 25 engageable with said blocks 16 mounted rigidly in the spaces between said walls. The end wall 24 is also formed with a tongue 27 which is engaged in a slot 28 in the plate 21 by the same adjustment of the upper portion of the casing.

110

that establishes said bayonet joint connection.

The removable portion of the casing must of course be normally locked in place, and 5 preferably this function is performed by the same locking member 8 that controls the rock-shaft. Thus there is mounted upon the barrel 9 a lug 27 engaging the hooked end 28 of a bolt 29 engageable in an aperture 30 of 10 a tongue 31 rearwardly projecting from one of the walls 23. A frame 33 within the housing 17 forms a mounting for the bolt 29 and a spring 34 coiled upon the bolt within said frame resists disengagement of the bolt from 15 said aperture 30. It will be apparent that so long as said bolt and tongue are engaged, there can be no longitudinal movement of the top portion of the casing with relation to the fixed bottom portion thereof, and consequently 20 there can be no unfastening of the bayonet joints which establish connection between the two portions of the casing.

To hold the lock adjusted in its various 25 positions of use, a spring detent 35 is employed, the same being engageable with any one of three notches 36 formed in the periphery of a disk 37 carried by the barrel of the lock. In two of the positions of the barrel determined by engagement of said detent in 30 said notches, the arm 10 is respectively vertical as shown in dash lines in Figs. 4 and 5 and inclined as shown in full lines in the same figures. When said arm is vertical the contact arms 6 are held raised above the 35 spark-plugs, this being the position of the parts when the engine is running. When the arm 10 is inclined, the members 6 bear upon the spark plugs, short-circuiting the same and thereby interrupting the circuit and rendering the engine inoperative. When the 40 detent engages the third notch, the lug 27 will have acted through the hook 28 to draw back the bolt 29, unlocking the top or cover portion of the casing so as to permit its removal.

Preferably the contact arms 6 will be formed of spring material so that in case one of said arms engages the corresponding spark-plug slightly in advance of the remaining arms, movement of the latter may still continue until all of the spark-plugs are short-circuited. The expression "interrupting the ignition circuit" as employed in the following claims is considered to cover 50 either completely opening said circuit or short-circuiting the sparking points so as to divert the ignition circuit to prevent the 55

functioning of the spark plugs and the operation of the engine.

What we claim is:

1. In a motor vehicle ignition lock, the 60 combination with the engine spark-plugs, of a casing inclosing said spark-plugs and comprising a portion permanently secured to the engine and a detachable portion, means for interrupting the ignition circuit at the 65 spark-plugs carried by the first-named portion of the casing, and a common means carried by the same portion of the casing for locking the interrupting means against actuation and for locking together the two portions of the casing.

2. In a motor vehicle ignition lock, the 70 combination with the engine spark-plugs, of a casing inclosing said spark-plugs and comprising a portion permanently secured to the 75 engine and a detachable portion, a rock-shaft mounted upon the fixed portion of the casing and grounded therethrough to the engine, contact arms carried by said rock-shaft for respectively bearing upon the spark-plugs in one position of the rock-shaft, a lock 80 through which the rock-shaft is actuatable, and means controlled by said lock for maintaining the two portions of the casing in engagement.

3. In a motor vehicle ignition lock, the 85 combination with the engine spark-plugs, of a rock-shaft mounted adjacent the spark-plugs, contact arms carried by said rock shaft for respectively bearing upon the 90 spark-plugs in one position of the rock-shaft, a spring acting upon said rock-shaft tending to effect engagement of the contact arms with the plugs, and a lock through which the rock-shaft is actuatable to disengage the contact 95 arms from the plugs.

4. In a motor vehicle ignition lock, the 100 combination with the engine spark-plugs, of a rock shaft mounted adjacent the spark-plugs, contact arms carried by said rock-shaft for respectively bearing upon the spark-plugs in one position of the rock-shaft, a lock through which said rock shaft is actuatable to positions effecting engagement or disengagement of the contact arms with the 105 spark-plugs, and a spring detent associated with said lock to maintain it fixed in various positions.

In testimony whereof we sign this specification.

ALF LANDGREN.
MAX B. EWERS.
